UNITED STATES PATENT OFFICE

CHARLES PECKERMAN, OF NEW YORK, N. Y.

DESIGN FOR A LAMP BULB

Application filed January 29, 1932. Serial No. 42,675. Term of patent 7 years.

To all whom it may concern:

Be it known that I, CHARLES PECKERMAN, a citizen of the United States, and residing at New York, in the county of New York and State of New York, have invented a new, original, and ornamental Design for a Lamp Bulb, of which the following is a specification, reference being had to the accompanying drawing, forming part hereof.

The drawing is a perspective view of a lamp bulb showing my new design.

I claim:

The ornamental design for a lamp bulb substantially as shown.

CHARLES PECKERMAN.
